ERNEST STARBUCK AND WILLIAM A. SEELYE, OF PEORIA, ILLINOIS; SAID SEELYE
ASSIGNOR TO FRED WILSON, OF MEDIAPOLIS, IOWA.

WINDOW-SCREEN.

1,250,376.

Specification of Letters Patent. Patented Dec. 18, 1917.

Application filed February 15, 1915. Serial No. 8,295.

To all whom it may concern:

Be it known that we, ERNEST STARBUCK and WILLIAM A. SEELYE, citizens of the United States, residing at Peoria, in the county of Peoria and State of Illinois, have invented certain new and useful Improvements in Window-Screens; and we do hereby declare that the following is a full, clear, and exact description of the invention, which will enable others skilled in the art to which it appertains to make and use the same.

This invention pertains to improvements in window screens. It relates particularly to the manner of constructing the frame of a screen and to the mode of holding and stretching the wire fabric.

An object of the invention is to construct a metal frame screen that will be practically indestructible, thoroughly strong and rigid in use, that can be readily assembled or disassembled by an inexperienced person, and that will be low in cost.

Another object is to construct a window screen in which the several parts of its frame, which may be termed its rails, are separable from one another and form other parts which hold the fabric so that the screen can be rewired, making use of certain corner braces for securing the several parts together.

Another object is to provide, in a window screen, a series of frame portions or rails each made up of two separable portions one inclosed by the other and inverted with respect to one another and so arranged that the inner one becomes the holding portion for the wire fabric while the other, the outer one, becomes the holding member for both the said inner portions with the fabric, the two in conjunction being adapted to draw or stretch the fabric tight in the act of assembling.

Still another object is to construct each frame portion or rail of a screen of two parts which after adjustment relatively to stretch the wire fabric can be secured in a desired adjustment by a corner brace by which to hold the fabric permanently stretched.

Besides these objects the invention relates to certain details of construction and ar-

angement of parts to be pointed out in the following specification aided by the accompanying drawings, in which,

55

Fig. 1 shows a piece of screen wire or wire fabric cut to a peculiar form and an inclosing U-shaped metal member placed on each of the two opposite edges.

60

Fig. 2 is a similar view showing the member turned in upon the wire fabric and a third member similar to the others placed on one of the other edges of the fabric.

65

Fig. 3 is a plan much enlarged showing the end of one of the members and the edge of the fabric inclosed therein.

65

Fig. 4 is a similar view showing the member turned over upon the fabric, the edge of the latter lying within it as in Fig. 3.

70

Fig. 5 is a view similar to Fig. 2 and on the same scale, showing all four edges of the fabric provided with the members shown in the preceding figures.

75

Fig. 6 shows a portion of the wire fabric in perspective and portions of two of the U-shaped members shown in the other figures, the same inclosing the edges of the fabric and turned over upon the latter together with certain other inclosing U-shaped members.

80

Fig. 7 is an elevation of substantially what is shown in Fig. 6, except that the said inclosing members are shown with finished mitered ends adapted to abut in use.

Fig. 8 is a cross section of the inclosing member of the upper rail of a lower screen, and the adjacent lower rail of an upper screen.

85

Fig. 8^a is a cross section of portions shown in Fig. 7 but in a corrugated form, the sides of the portions being purposely widely spaced to clearly show the structure.

90

Fig. 9 is an elevation of one of the upper corners of a lower completed screen and a portion of the lower corner of an upper screen showing their relation and their position upon a track.

95

Fig. 10 is a plan showing the relation of the two screens shown in Fig. 9.

Fig. 11 is an elevation of an upper and a lower screen showing a part of the latter in section, and of a corrugated form corresponding with Fig. 8^a.

100

Fig. 12 is a cross section of one of the

rails of a screen inclosed in one of the corner braces.

Fig. 13 shows two guides one for an upper screen and one for the lower screen.

Fig. 14 is a plan showing a modified form 5 of track in cross section and the manner of mounting the screens therein; and,

Fig. 15 shows a corner bracket in perspective.

10 Screens made up of wooden frames are very difficult to properly "rewire", are destructive, and the process of rewiring is very tedious and not easily accomplished by one not skilled in such work. It is our 15 purpose to provide a form of metal frame for a screen that will be practically indestructible and of a form such as will admit the most inexperienced person to rewire the screen in a short time with a minimum of 20 effort, and above all the fabric of the completed screen will have been stretched perfectly tight, because of certain necessary acts to accomplish the reassembling of the parts.

We are aware that it is not new to construct screens of metal since we have knowledge of a number of patented devices. But in bringing out the form of screen now to be described simplicity is the first requirement so that the parts may be readily and 30 easily assembled and disassembled, also that it shall be low in cost because of its simple construction and that any person entirely inexperienced in handling tools or of performing any sort of mechanical work can 35 do all work necessary in rewiring the screen or taking general care of it. In order that the construction of the screen and its manner of handling can be most easily and clearly understood, the drawings have been 40 prepared with a view to illustrating the several steps in putting the screen together.

In the figures A represents a piece of screen wire, or wire fabric of the proper size of a given screen to be assembled, it being 45 observed that each corner of the fabric is recessed as shown at A'. Each of the edges of the fabric is now inclosed in a channel member of metal B plainly shown in plan in Figs. 3 and 4. The width of each member B is substantially equal to one half of 50 the width of that portion of the screen projecting outward from the recess. Upon being placed as described each member is turned over upon the fabric as shown in Fig. 4, thus bending the wire along the edge of the members as shown clearly in Fig. 6. Fig. 2 shows three of these members thus placed and turned over upon the fabric leaving the fourth edge free. Fig. 5 shows the 55 four edges complete in this respect.

It is observed that the length of each member B is substantially equal to the length of the edge of the fabric between the recesses. By recessing the corners, as 60 explained, after the members B are turned

in, there are no parts of the fabric exposed or that will prevent the easy handling or manipulation of the parts described.

C represents a channel member placed over each of the members B and the fabric adjacent thereto, this being entirely disclosed in Figs. 6, 7, 9, 11 and 12. The recesses or channels of these members C are such as to receive each member B and the wire fabric in a snug fit as clearly shown in said Figs. 75 11 and 12. The ends of said members are mitered and the shortest measurement of said members, or that between the innermost corners thereof, is substantially equal to the length of the members B. 80

D represents a corner brace or fitting of sheet metal. It is designed to receive and inclose the ends of the members C at each corner of the screen and for this purpose when placed in position are slightly spread 85 so as to be sprung over said members when the parts are assembled with the fabric. In Fig. 9 the assembled relation of the parts is shown by dotted lines X indicating the abutting mitered edges of the members C. 90 The latter when assembled within the said corner brace D represent the full outer measurement of the screen to fit between tracks or guides indicated at E, Figs. 9, 10 and 14. 95

The wire fabric when prepared for use is cut to a certain size and when the members B are placed thereon and turned over upon it as already described, the distance between the inner edges of two opposite ones must 100 be preferably slightly less than the distance between the inner edges of the opposite members C corresponding in position thereto. This relation provides for tightly stretching the fabric in the completed screen. The 105 dotted lines in Fig. 9 indicated by B represent the members B as the position they occupy before the fabric which they hold is stretched. The last act in the assembling operation is now to stretch the fabric. This 110 is done by employing a clamp for ease and convenience, one part of which lies upon the outer surface of the member C and the other upon the inner edge of the member B. Now, by drawing up the clamp, B is forced 115 inward into C to substantially the position shown in full lines in said Fig. 9 whereupon a screw F is inserted through holes G in the brace D, Fig. 14, one of which may be threaded to receive the threaded portion of 120 the screw which, when tightened, firmly clamps said brace upon the part inclosed by it. The screw may serve to prevent the movement of the members B outward, although the friction set up by clamping the 125 brace will be sufficient. That is to say, the screw since it lies in the angle of the frame can lie sufficiently close to the members B so they can each bear upon it and, of course, said screw will pass through the fabric, the 130

latter being spread to form a hole α as shown in Fig. 7 by means of awl or similar implement to make room for the introduction of the screw.

5 The stretching action will preferably take place simultaneously at all four edges so that the braces D can all be tightened at once. The brace is paneled at F so that in moving the sides toward one another the 10 edges that underhang the members C, as shown in Fig. 12, will result in firmly inclosing those parts. However, outward from the screw the metal is not indented but lies in the same plane with the outer- 15 most surface of the side of the brace to receive a certain guiding portion J about to be described.

During the act of stretching the fabric the abutting mitered ends of the members C 20 held within the braces D are the parts upon which the strain is placed in the clamping operation and these also maintain the fabric in its permanently stretched condition.

Fig. 14 shows a form of double track to 25 receive the upper and lower screens in separate guideways but where a single track is employed, which is preferable from the fact that the screens can be removed without disturbing or removing the track, guides are 30 provided for each screen and these are clearly shown in Figs. 9, 10 and 13. In Fig. 10 the track has a single metal guiding portion H which lies between the screens. J indicates a guide for each screen, the same 35 being provided with a threaded hole L to receive the end of the screw G, as shown in Fig. 11, which is made long enough to engage it. The free end of the guide is bifurcated so as to provide an upper and a lower 40 extension or tongue, one of which is bent beyond the plane of the other as clearly shown in Fig. 13, whereby, as shown in Fig. 10, one of the said tongues lies at each side of the said guiding portion H of the track.

45 The corner brace D is provided with integral projections M as shown in Fig. 15, which are formed by forcing the metal outward. One of these projections lies at each side of the said guiding portion J and 50 holds the same in its proper position in use. The said members J are duplicates, one being inverted to take its place upon the upper screen.

Each corner brace D is provided with 55 one of said members and thus the screen is held in its proper position while permitting it to be readily raised and lowered. In order to permit removal of the screens from the window, the screws are loosened sufficiently to permit the portions J to slip over the upper projection M described away from the tracks. This constitutes a very simple and effective form of guide which also permits the screen to be removed in but a 60 moment or two.

Though not shown, any suitable friction device may be employed to hold the upper screen in its proper position and to hold the lower one in any raised position and in fact if constructed of spring-metal the 70 guides J themselves may constitute the friction means to grasp the guiding portions H of the track.

It is observed that since the edge of the fabric A lies within the channel member B 75 and is thus recurved upon itself no amount of strain upon the fabric in stretching it can possibly withdraw it from said member B besides the fact that the channel members C also assist in preventing such an occurrence.

The structure throughout is quite simple and the act of assembling its parts and stretching the fabric is really more simple than would appear from the description. 85

In practice, the measurement of the fabric when cut for use is such that when the members B are placed upon its edges and folded over upon it, as described, the measurement between the inner edges of the said 90 members B in a folded position (Figs. 5 and 6) will be slightly less than the distance between the inner edges of the members C in their assembled relation, so that when drawn to the finished assembled position, 95 the tight flat fabric is the result.

In rewiring the screen the simple removal of the four screws and the spreading of the corner braces permits the members C to be withdrawn whereupon the members B can 100 be removed and thus readily slipped from the edges of the fabric. A new piece of fabric having been cut in the manner explained can then be employed and the parts reassembled.

105 The thickness of the part H of the track E, Fig. 10, has purposely been exaggerated as well as the part corresponding to it in Fig. 14, in order that the drawing can be easily read and that the structures can be 110 more readily observed. However, in practice, the meeting rails of the upper and lower screens can lie quite close together by making the equivalent of the said portion H quite thin. But where a space may exist 115 between them such as would admit insects to crawl between the rails the metal of the member C of the lower screen may be turned outward into a flange C', Fig. 6, to meet the opposite lower rail of the upper screen, or, 120 as shown in Fig. 8, the edge of the member C of the lower rail of the upper screen may be outwardly bent in the same manner toward the lower rail as shown at C². But in any event the braces D will lie close enough 125 to one another for all purposes.

In Figs. 8^a and 11 the sides of the members B and C are corrugated. This answers two purposes, first, that of strengthening said members to guard against being bent 130

out of shape by blows that said members may accidentally receive, and second, when the members B are forced into the members C in the manner already explained, the corrugations will aid materially in preventing movement of the parts relatively. However, for the latter purpose the parts may be otherwise provided with roughened surfaces not necessarily coming under the head of 10 corrugations.

The structure described herein may be employed equally well for half length screens or those to extend the full length of the window and hung from the top to swing 15 outward. In the two piece form herein illustrated the screens because of their thin form can be placed between the window and outside blinds so as not to interfere with either which is an advantage well understood. 20

A point of advantage also is that the parts of the screen, besides the fact that they can be easily taken apart and reassembled, are not liable to damage in so doing where- 25 as in some forms of patented devices with which we are familiar the parts cannot be separated without destroying their utility.

The fact that the sides of the members B lie close together or so close as to just receive the thickness of the fabric and that the sides of the members C are spaced just sufficient to receive the said members B and the additional thickness of fabric at the side as in Fig. 12 insures a strong rail for the screen 30 at all sides in addition to the fact that the fabric is so firmly held that it cannot become loosened, aided by the sharp turn of the fabric over the edge of said members. B. 35

While we have described a peculiar manner of constructing the portions of the screen they may be altered in various ways to suit the desires, or to best meet the aim of the invention, all without departing from the spirit of said invention and the meaning 40 of the appended claims.

Having thus described our invention, what we claim as new and desire to secure by Letters Patent is:—

1. In a screen, the combination of a main 50 frame, consisting of channeled members fixed relatively and permanently and open at their inner edges which face one another, a member inclosed in each of the channeled members, a screen fabric each of whose 55 edges is secured relatively to each inclosed member, all the inclosed members being separately adjustable outwardly in the plane of the fabric into the said channeled members, and means to clamp all of the inclosed members in the channeled members together but permit the adjustment of the 60 former relatively to the latter.

2. In a screen, the combination with its 65 covering fabric, of a separate member at each of the four edges of the fabric, the

edges of the latter being carried by the said members, a frame forming the boundary of the screen, and within which the members are inclosed and in which each is adjustable independently of one another and of said frame in an outward direction in the plane of the fabric to stretch the latter, and means to clamp the members within and relative to the frame. 70

3. In a screen, the combination with its 75 fabric, of a separate channel member lying at each of four edges of the fabric, the open channels of opposite members facing outward in opposite directions, the edges of the fabric lying in said members, a frame each 80 part of which has a channel facing inward toward one another, the described members lying therein and separately adjustable relatively thereto, and means to secure said members and the frame relatively. 85

4. In a screen, the combination of its wire 90 fabric, a separate independent U-shaped channel member forming a part of each of the four sides of the frame of a screen frame, the open channel of all of the members facing outward, the edge of the wire fabric lying within said open channels, a second U-shaped channel member overlying and inclosing each of the first and the fabric, all of the second members being secured 95 relatively as a rigid frame, the said first members being adjustable within the frame, and means to secure all of the described members relatively.

5. In a screen, the combination of its wire 100 fabric, a separate U-shaped channel member in each of which one of the edges of the said fabric is inclosed, the sides of the members being closed upon said fabric but permitting its withdrawal therefrom, said members being each turned over upon the fabric and all of them lying substantially in the same plane, a frame composed of U-shaped channel members the open portion of each facing inward toward the corresponding opposite 110 portion, and each adapted to receive into it one of the first named channel members, the latter being adjustable therein in the plane of the fabric in an outward direction to stretch said fabric, and means to secure the members 115 relative to each other and said frame.

6. In a screen, the combination of its fabric, a separate member adapted to receive one of the edges of said fabric, the latter being detachably secured to each, separable U-shaped 120 members constituting part of the frame of the screen, the open channels of the members facing inward toward opposite members of said frame and each adapted to receive one of the first named members, the latter being independently adjustable relative to one another and relative to said frame 125 to stretch the fabric, and means to secure the frame and said first named members relatively. 130

7. In a screen, the combination of its fabric, a separate member for each edge of the fabric, the edges of said fabric being detachably held on the members, a hollow frame comprising channel members abutting at their ends and in use fixed relatively, their open sides facing inward toward one another, the first named members lying therein and adjustable independently relative to the frame members, a brace for each corner of the frame including opposite clamping portions to engage the said frame members and adapted for holding them in their abutting relation, and means to clamp the portions of the brace upon the frame members and for clamping the inner fabric carrying members relative thereto.

8. In combination, the frame of a screen consisting of metal having roughened surfaces, and a separate and independent holding member for holding each edge of the screen fabric and having correspondingly roughened surfaces adapted to engage those of the frame and separately adjustable within the frame each in an outward direction to stretch said fabric, and means to secure the members and the frame relatively.

9. In combination, the frame of a window or other screen consisting of corrugated metal, the corrugations extending longitudinally of the frame parts, a separate and independent holding member for each edge of the screen fabric and having correspond-

ing corrugations extending longitudinally thereof adapted to engage those of the frame and separately adjustable within the frame each in an outward direction to stretch said fabric, and means to secure the members and frame relatively.

10. The combination of the meeting rails of an upper and lower screen section movable relatively each comprising a channeled member inverted in position with respect to one another, one of said members including an extension projecting toward the other and spanning the space between them and guides relative to which the sections are movable in planes parallel to one another.

11. The combination with a window screen and a track for the same including an extended portion lying parallel to the plane of said screen at one side thereof, of a member secured on the screen including spaced extensions adapted to engage opposite sides of said extended portion for securing the screen in position and guide it in said track, said member being pivotally mounted on the screen and adapted to swing in its own plane away from the said track.

In testimony whereof we affix our signatures, in presence of two witnesses.
